UNITED STATES PATENT OFFICE.

JOHN NESVADBA, OF BINGHAMTON, NEW YORK, ASSIGNOR OF ONE-THIRD TO STEVE KRNA, OF BINGHAMTON, NEW YORK.

MASK.

1,101,756.

Specification of Letters Patent. Patented June 30, 1914.

Application filed February 7, 1914. Serial No. 817,206.

To all whom it may concern:

Be it known that I, JOHN NESVADBA, a subject of the Emperor of Austria-Hungary, residing at Binghamton, in the county of 5 Broome and State of New York, have invented certain new and useful Improvements in Masks, of which the following is a specification.

This invention relates to certain new and 10 useful improvements in masks.

An object of the invention is to provide a mask for firemen that will permit the firemen to enter burning buildings filled with smoke and which will not in any way interfere with the vision or breathing of the men. 15

A further object of the invention is to provide a mask formed of absorbent material, preferably sponge, that is to be saturated with water or other fluid and having 20 eye openings therein carrying lenses and further provided with adjustable elastic strap connections whereby the same may be adjusted to heads of different sizes.

With the above and other objects in view, 25 that will appear as the nature of the invention is better understood, the same consists in the novel construction to be hereinafter more fully described and then claimed, reference being had to the accompanying drawings 30 by characters denoting like parts throughout the several views and in which:—

Figure 1 is a perspective view of the mask illustrating its manner of use. Fig. 2 is a 35 rear face view illustrating the manner of connecting the straps thereto. Fig. 3 is an enlarged cross sectional view taken on the line 3—3 of Fig. 2, illustrating the manner of positioning the vision lenses in the mask, 40 and Fig. 4 is an enlarged sectional view taken on the line 4—4 of Fig. 2 illustrating the manner of connecting the straps to the mask proper.

It is a well known fact that firemen are 45 often rendered unconscious by the dense smoke within a burning building and with an object to overcome the danger incident thereto, I have provided a face mask formed of absorbent material to be worn by firemen 50 and having eye openings therein provided with lenses. The absorbent material is to be saturated with water or other fluid which will prevent the passage of smoke or gases through the absorbent material, while the 55 lenses in the mask will permit the wearer to

discern objects and at the same time protect the eyes.

Referring more specifically to the drawing accompanying this application, the reference numeral 10 denotes a face mask of a 60 shape suitable to cover the major portion of the face, extending from the forehead to a point below the chin and covering a portion of the cheeks of the wearer.

The invention will be better understood 65 by referring to Fig. 2 which shows a rear face view of the mask. The mask 10 is formed of absorbent material, preferably sponge.

Eye openings are provided in the mask 10 70 adjacent the upper end thereof so that when the mask is in position upon the face the said openings will be aligned with the eyes of the wearer and positioned within the eye openings are the lenses 11. The lenses 11 are 75 carried by ring members 12. Secured to the mask 10 at a point adjacent the upper end thereof is a strip of material 13 which may be either light leather or other suitable non-absorbent fabric, the strip 13 having open- 80 ings therein which register with the eye openings in the said mask. The edges of the openings in the strip 13 are turned into the eye openings in the mask 10 as at 14. The strip 13 is secured to the mask 10 by 85 stitching 15 which preferably passes completely through the mask 10 to insure the stability of the parts.

The mask 10 is provided with reinforcing strips 16 and 17 of non-absorbent material, 90 the strips 16 being stitched to the inner side of the cheek portions as at 18, while the reinforcing strip 17 is stitched to the chin portion as at 19, the stitching 18 and 19 passing completely through the mask 10 as shown in 95 Fig. 4.

Means are provided for securing the mask 10 to the head of a wearer and consists of elastic straps 20 and 20', the strap 20 being secured to the end of the strip 13 by stitching 21 while the strap 20' is secured to the meeting ends of the reinforcing strips 16 and 17 as by stitching 22. These elastic straps 20 and 20' are connected together at their opposite ends as at 23 and secured to 100 the meeting ends 23 is the buckle strap connection 24.

It will be readily discerned from the above 110 description of the device that the several parts shown are so connected as to render the

device practically indestructible, and should either of the lenses 11 become broken the retaining rings therefor may be readily removed and new lenses placed therein. These rings 12 may be permanently secured in the mask 10 or be frictionally held therein by the said ring engaging the turned in portion 14 of the strip 13.

While I have shown and described the preferred embodiment of my invention, I do not wish to confine myself thereto, as various forms and modifications may be had which fall within the spirit and scope of the invention as claimed.

15 I claim:—

1. A fireman's face mask formed of a sheet of absorbent material having eye openings therein, a strip of non-absorbent material carrying lenses secured to the inner side 20 of the mask, said lenses to be received in the eye openings, elastic straps secured to the non-absorbent strip and buckle straps carried by the elastic straps.

2. In a face mask, a shield of absorbent material having eye openings therein, a strip of non-absorbent material carrying lenses stitched to said shield, said lenses to be received in the eye openings, cheek and chin reinforcing strips stitched to said shield,

30 and buckle straps stitched to said reinforcing strips, all of said stitching passing completely through the mask.

3. A face mask, comprising a shield of sponge or like absorbent material formed with eye openings, a reinforcing strip secured to the inner side of said shield, lenses 35 secured to said strip, vertically-disposed reinforcing strips on the inner side of said shield, and buckle straps secured at their inner ends to said reinforcing strips for securing the mask to the wearer's head.

4. A face mask comprising a shield of absorbent material formed with eye openings, a reinforcing strip of non-absorbent material having eye openings, flanged lens frames 45 fitting within the openings in said strip, lenses held in said frames, reinforcing strips also of non-absorbent material disposed vertically on the inner sides of the shield, and securing straps secured to said reinforcing 50 strips.

In testimony whereof I affix my signature in presence of two witnesses.

JOHN NESVADBA.
